William W. Stevens, of Westbrook, Maine.

Assignor to

Nath. P. Richardson & Co, of Portland, Me.

Letters Patent No. 1119. Dated July 5, 1859.

The schedule referred to in these Letters Patent and making part of the same.

To all whom it may concern:

Be it known that I, William W. Stevens, of the Town of Westbrook, County of Cumberland and State of Maine have invented or produced a new and original design for a Top, Front "jamb" or sides for a Fire Frame and I do hereby declare that the following is a full and exact description of the same.

Of the said drawings

Figure 1. denotes a perspective elevation of my design of which E, E, E, — represent the Front, F, the Tops, and G, G, the sides or "jamb" of the Fire Frame.

Figure 2, is a vertical section of the Top & front taken through the line A, B.

Figure 3, is a transverse section of the Top taken through the line C, D.

Figure 4, is a transverse section of the "jamb" or side and front taken through the line M, N.

I claim the configurations ornaments and moldings above described as shown in the drawings as a design for Fire Frames.

In testimony whereof I have hereunto set my hand and Seal this second day of June A. D. 1859.
